UNITED STATES PATENT OFFICE.

VIRGIL BROWNE, OF OKLAHOMA CITY, OKLAHOMA, ASSIGNOR TO OKLAHOMA COCA COLA BOTTLING COMPANY, OF OKLAHOMA CITY, OKLAHOMA, A CORPORATION OF OKLAHOMA.

BOTTLE-CAP DISPENSER.

Application filed December 4, 1926. Serial No. 152,642.

In the bottling of beverages, a common method of sealing the filled bottles is by the use of the crown cap (a metal disc over a cork disc, the former having ruffled edges turned down over the lip of the bottle). These caps are decorated to show the various names of flavors, and when put on bottled beverages of the flavor shown on the cap form a means of identification or description of the beverage contained in the bottle.

Before the caps are attached to the bottles they are put into a hopper arrangement on the capping (or crowning) machine, from which they are fed automatically, one at a time, to the device which presses them over the lip, or rim, of the bottles.

Heretofore, when it was desired to bottle a certain flavor, it was necessary to put the caps labelled for that particular flavor into the hopper of the crowning machine by transferring them in buckets or other small receptacles from the shipping container in which received from the factory.

Under such procedure, when it was desired to stop bottling a particular flavor and start bottling a beverage of a different flavor, it was necessary to fill the hopper with caps for the new flavor by the same laborious process of transferring and depositing the crowns in the crowning machine by means of buckets.

Another great disadvantage in the handling of caps in that manner is in the risk that is run of having them become dusty or otherwise contaminated once the original shipping package has been opened. This may result in damage to the beverages on which they are used, or financial loss through the necessity of discarding such contaminated caps.

To avoid this repeated handling of caps is the purpose of this invention, as well as to eliminate the attendant risks referred to by providing a dustproof, insect-proof, and sanitary container for said caps while not being actually fed into the crowning machine.

The invention is illustrated in the accompanying drawings, in which Figure 1 is an elevation of the device, Figure 2 is a plan view of the device; Figure 3 is an enlarged

vertical sectional view of one of the bins; Figure 4 is an elevation of the parts shown in Figure 3; and Figure 5 is a detail sectional view on the line 5—5 of Figure 3.

As shown in Figures 1 and 2, the device consists of a series of individual bins 10 arranged circumferentially on a metal frame base 11, with means of holding them rigid against a central pipe 12—13 leading into the hopper of the crowning machine (not shown), and each such bin 10 having an opening, or valve 14, leading into the central feed pipe 12.

This device may be located on the floor above, or on a loft over, that on which the crowning machine is situated, with the central feed pipe 12 connecting with the hopper (not shown) of the crowning machine 70 through an aperture in the floor.

Each of the bins 10 may be used as a container for crowns bearing the label for one flavor of beverages, and the gravitational flow of such crowns from each bin down through the central pipe 12 into the crowning machine is regulated by a combination valve-agitator 14—15, hereinafter described, connected with each bin at its lower and inner side.

The bins are metal, and are made to open in the manner shown, thereby making a sanitary and dustproof compartment when the crowns have been placed therein and the hinged top closed. Each bin has an inclined bottom 16 slanting toward the inner side, and valve opening 14 referred to, in order to induce and accelerate gravitation of the crown caps toward such opening.

This valve consists of a ball bearing 17, 90 rotatable elbow pipe 18, through which the crowns will flow when the pipe is turned open side down, and from which the crowns will not flow when the open side is turned upwards. Each valve is operated by a lever 19 with cord 20 attached and controlled over a system of pulleys 21, the lever 19 being equipped with a spring 22 to hold and return the valve to the "closed" position.

Each valve is fitted with a collar 23 having a slot 24 in it, through which a pin 25 projects from the inner connection with the bin. This slot and pin controls the rotation of the valve so that neither will the opera-

tion of the lever 19 rotate the valve, or pipe, beyond the downward position nor the operation of the spring 22 on the lever 19 return the pipe to a position beyond the upward position necessary to stop the flow of bottle caps.

Being flat objects, and especially in view of the skirt on the edge which renders one side concave, crown caps have a tendency to nest one inside the other as well as to clog unless kept loose.

To prevent this and to facilitate their movement from the bin through the valve into the central feeding pipe, the rotatable pipe elbow is equipped with an agitator 15 designed to stir up the caps in the bin and in the pipe.

This agitator consists of a shaft 26 which extends from the socket in which it is set in the outer side of the bin through the valve opening 14 and is anchored on the wall of the elbow pipe 18. A series of short rods 27 are attached crosswise and to this main agitator shaft 26, thereby forming a means of agitating the caps packed in the bin when the main agitator rod is revolved.

The socket in which the rod is set on the outer side of the bin allows free movement of the main agitator rod at that point, and the connection of said shaft with the elbow pipe is the means by which such main agitator shaft is put in motion, this being done by the movement of the valve from "closed" to "open" position, and vice versa. When such valve, upon which the end of the agitator rod is anchored is moved, it carries the rod with it in a semi-circular movement, the contact of the rod and its cross-rods in the bin coming in contact with the crowns and keeping them loose in order that they may flow freely through the valve.

The cords attached to the valves, and by the pulling of which the valves are operated, are controlled over a system of pulleys to the floor on which the crowning machine is located. In this way the operator of the crowning machine may, by a series of pulls on a particular cord, control and obtain a flow of the kind of crowns desired from its respective bin into the hopper of the crowning machine. When the quantity desired is obtained the flow may be stopped by releasing the cord. The crowns remaining in the bin, or bins, may then be left there without

further handling until the same kind is again required.

While the device described herein specifies the position of the bins to be circumferentially around a main feeding pipe, it is to be understood that the position of the bins may be varied so long as connection is still maintained with the central feed to the capping machine without departing from the spirit of the invention or the scope of the subjoined claims.

Having described my invention I claim:

1. A dispensing device including a bin and having a valve or discharge outlet, an agitator pivoted in the bin and attached to the valve whereby the valve and agitator are concurrently operated during a dispensing operation.

2. A dispensing device including a bin and having a rotary valve, an agitator pivoted in the bin and attached to the valve whereby the valve and agitator are concurrently operated during a dispensing operation.

3. In a combination bottle cap feeding and storing device, a bin with a combination valve-agitator, consisting of a valve opening on the bin, the movement of said caps being assisted and accelerated through said opening by means of an agitator shaft attached to and extending from a socket in the wall of said valve to a socket in the outside wall of said bin, and having rods attached crosswise thereto, so that the movement of such valve agitates said shaft and prevents congestion of the caps in said bin or opening.

4. In a combination bottle cap feeding and storing device, a bin with a combination valve-agitator consisting of an elbow pipe rotatable upon its connection with the bin, said pipe being rotated into downward position for delivery of the caps by means of a lever attached to the side of said pipe, and returnable to its upward position by means of a spring on said lever, and having a shaft attached to and extending from a socket in the wall of said valve to a socket in the outside wall of such bin, and having rods attached crosswise thereto, so that the movement of such valve agitates said shaft and prevents congestion of the caps in said bin or opening.

VIRGIL BROWNE.
